(57) **CLAIM**

We claim the ornamental design for a watertight decking panel, as shown and described.

DESCRIPTION

FIG. 1 is a perspective view of the watertight decking panel according to the design of this invention, where the upper surface shows a simulated wood grain.

FIG. 2 is an end view thereof;

FIG. 3 is an end view thereof showing the opposite end;

FIG. 4 is a top view thereof;

FIG. 5 is a bottom view thereof;

FIG. 6 is a lateral side view; and,

FIG. 7 is a lateral side view of the opposite side.
